UNITED STATES PATENT OFFICE

JESSE DITSON, OF LITTLETON, COLORADO, ASSIGNOR TO INGERSOLL-RAND COMPANY,
OF JERSEY CITY, NEW JERSEY, A CORPORATION OF NEW JERSEY

SUPPORT FOR IMPLEMENT RETAINERS

Application filed April 19, 1927. Serial No. 184917.

This invention relates to drill sharpeners, but more particularly to a support for a retaining spring used for retaining the forming dolly in operative position in the hammer cylinder of the drill sharpener.

One object of the invention is to facilitate the operation of securing the dolly retainer in operative position.

Other objects will appear hereinafter, and to all of these ends the invention consists of the combination of elements and arrangement of parts having the general mode of operation substantially as hereinafter described and claimed and illustrated in the accompanying drawings, in which

Figure 1 is a longitudinal sectional elevation of a portion of a drill sharpener showing the dolly retainer about to be pressed into engagement with the carriage,

Figure 2 is an end elevation partly broken away of the hammer cylinder showing the dolly retainer in operative position,

Figure 3 is a view similar to Figure 1 illustrating the manner in which tension is induced in the retainer springs, and

Figure 4 is a sectional plan view taken through Figure 3 on the line 4-4 looking in the direction indicated by the arrows.

Referring to the drawings, A designates a portion of the casing of a drill sharpener having a support B on which is disposed slidably a hammer cylinder C. The means for securing the hammer cylinder C in the desired position with respect to the support B are not shown in the drawings, but it is to be understood that any suitable and convenient means may be provided for this purpose.

Disposed within the cylinder C is a reciprocating hammer piston D adapted to be actuated by pressure fluid controlled and conveyed to the cylinder C in any well known manner. The hammer piston D has a forward reduced extension E which operates slidably with a washer F in the front end of the cylinder and extends into a bore G in a front head H supported by the cylinder C.

The forward portion of the bore G of the front head H is preferably reduced some-

what in diameter to receive slidably a forming dolly J adapted to form the cutting face of the working implement, such as a drill steel K supported by the casing A. The rearward portion of the dolly J extends into the enlarged portion of the bore G and is exposed to the blows of the hammer piston D.

Carried by the cylinder C is a carriage L having a pair of forwardly extending arms O preferably parallel with respect to each other and located at opposite sides of the carriage L. The carriage L in this instance is secured to the cylinder by means of bolts P and at their forward ends and on the inner surfaces thereof are formed lugs Q having inclined grooves R. The arms O are further provided on their inner surfaces with trunnions S preferably located at a point above the grooves R of the lugs Q. The end surfaces T of the trunnions S are in this instance tapered or inclined and in the periphery of the trunnions S are formed concave annular grooves U for engagement with the outer coils of lateral spring members V formed integrally in this instance with a retainer yoke W adapted to engage a slot X in the dolly J. The outer coils of the springs V preferably have terminals Y which, when the springs are in engagement with the trunnions S, will lie in the grooves R of the lugs Q.

Any suitable means may be provided for forcing the springs V into engagement with the trunnions S. In the present instance, the means provided for this purpose consists of a projection Z located on the side of the casing A and having a surface b lying in a plane somewhat above the longitudinal axes of the trunnions S.

In practice, the dolly J is first placed in the front head H in such a position that the slot X is pointed downwardly to receive the yoke W and the springs V of the yoke will then abut the lugs Q in the manner illustrated in Figure 1. After the dolly and the yoke are thus disposed, the hammer cylinder C may be advanced in the direction of the casing A with sufficient force to enable the projection Z to force the springs

V into the carriage L. In this way, the springs V will be guided into engagement with the grooves U by the inclined surfaces T of the trunnions S, and the spring terminals Y will lie in the grooves R at a suitable angle to the yoke so that sufficient tension will be set up in the springs to enable the yoke W to promptly retract the dolly J after each blow of the piston.

10 By means of this invention the operation of inserting the yoke W in the carriage L has been greatly simplified, and the chances of injury to the operator have been practically eliminated.

15 I claim:

1. In a drill sharpener, the combination of a casing, a hammer cylinder carrying a forming dolly, a carriage on the cylinder, a spring retaining the dolly in operative position, there being means on the carriage adapted to engage the spring for holding said spring in operative position, and means for guiding the spring into engagement with the first said means whenever the spring is 25 forced into contact with the casing.

2. In a drill sharpener, the combination of a casing, a hammer cylinder carrying a forming dolly, a carriage carried by the cylinder, means comprising a yoke with integral spring members for retaining the dolly in operative position, there being trunnions on the carriage adapted for engagement with ends of the springs to hold the yoke in operative position, and said carriage having means for guiding the springs into engagement with the trunnions.

3. In a drill sharpener, the combination of a casing, a hammer cylinder slidable relatively to the casing, a carriage secured to the cylinder, means comprising a yoke with integral coil springs for retaining the dolly in operative position, there being trunnions on the carriage engaging end coils of the springs to maintain the yoke in operative position, and inclined surfaces on the trunnions to guide the springs into engagement with the trunnions whenever the carriage is advanced to force the springs into contact with the casing.

4. In a drill sharpener, the combination of a casing having a projection, a hammer cylinder slidable relatively to the casing, a carriage carried by the cylinder, arms on the carriage, a forming dolly, means comprising a yoke and integral lateral coil springs for retaining the dolly in operative position, there being trunnions on the arms having grooves to engage the coils of the springs, and inclined surfaces on the trunnions to guide the springs into the grooves upon the application of pressure against the springs by the projection.

5. In a drill sharpener, the combination of a casing having a projection, a hammer cylinder slidable relatively to the casing, a

forming dolly, a carriage movable with the cylinder having a pair of arms, means comprising a yoke and integral springs for retaining the dolly in operative position, there being trunnions on the inner surfaces of the arms, said trunnions having external annular grooves to engage end coils of the springs, there being means on the arms supporting terminals of the springs to induce tension in said springs, and inclined end surfaces on the trunnions to guide the springs into engagement with the grooves whenever the springs are pressed against the projection.

6. In a drill sharpener, the combination of a fixed member, a movable member carrying a working implement, yieldable means for retaining the working implement in the movable member, and means carried by the movable member adapted to be forced into engagement with the yieldable means whenever said yieldable means are pressed against the fixed member by the movable member to place the yielding means in operative position to maintain the working implement in the moving member.

7. The combination of a drill sharpener and a support for the work, of a hammer cylinder carrying a forming dolly, a carriage carried by the cylinder, a spring for retaining the dolly in operative position and adapted to be placed in front of the carriage preparatory to the movement of the same and in engagement with the dolly, and means for guiding the spring into the operative position as the carriage moves toward the support to retain the dolly in the operative position.

8. The combination with a drill sharpener having a carriage and a support for the work, of a hammer cylinder carrying a forming dolly, a spring for retaining the dolly in position, there being means on the carriage for holding the spring in operative position to retain the dolly, said means being adapted to be pressed into engagement with the spring as the carriage is moved toward the support for locking the spring in an operative position.

In testimony whereof I have signed this specification.

JESSE DITSON.
